UNITED STATES PATENT OFFICE.

WILLIAM J. VAN OSDEL, OF CHICAGO, ILLINOIS.

CLIPPER.

Application filed June 3, 1926. Serial No. 113,412.

This invention relates to improvements in clippers, particularly adapted though not necessarily limited in its use in barber shops, and one of the objects of the invention is to 5 provide an improved device of this character wherein the actuating mechanism embodies an electro-magnet which controls the vibration of an armature, both the armature and magnet being located within the handle 10 of the device, the clippers being operated by means of the electro-magnet to which alternating current is supplied.

A further object is to provide in a clipper of this character, improved means whereby 15 a vibrator or massage device may be readily connected to the armature and improved means for controlling the extent of movement of the armature under the influence of the electro-magnet in accordance with the 20 work to be performed by the device.

A further object is to provide an improved device of this character which will be of a simple and compact construction, effective and efficient in operation, and of a size and 25 shape convenient to be readily handled by an operator.

To the attainment of these ends and the accomplishment of other new and useful objects as will appear, the invention consists in 30 the features of novelty in substantially the construction, combination and arrangement of the several parts hereinafter more fully described and claimed and shown in the accompanying drawings illustrating this invention 35 and in which

Figure 1 is a top plan view of a device of this character constructed in accordance with the principles of this invention.

Figure 2 is a side elevation of Figure 1.

40 Figure 3 is a top plan view of the device with the cover section removed and showing a vibrator attached to the armature.

Figure 4 is a longitudinal sectional view taken on line 4—4, Figure 1.

45 Figure 5 is a detail transverse sectional view taken on line 5—5, Figure 3.

Figure 6 is a detail perspective view of one portion of the casing and a portion of the armature.

50 Figure 7 is a detail sectional view taken on line 7—7, Figure 3.

Figure 8 is a detail sectional view taken on line 8—8, Figure 4.

55 Figure 9 is a detail sectional view taken on line 9—9, Figure 3.

Figure 10 is a detail perspective view of the armature.

Figure 11 is a detail plan view of the spring washer for maintaining the controlling member for the armature in its adjusted position. 60

Figure 12 is a detail perspective view of a vibrator attachment.

Referring more particularly to the drawings the numeral 15 designates an open casing of any desired size and configuration, at 65 the forward end of which is secured a stationary cutter member 16, the latter being preferably arranged at an angle to the longitudinal axis of the casing and being provided with teeth 17, usual in cutters of this character. 70

Reciprocating upon the cutter member 16 is a cutter 18 which is guided in its action preferably by means of a member 19 secured thereto and which operates in a groove 20 in the upper face of the member 16. 75

Arranged within the casing 15 is an electromagnet 21, the core 22 of which is provided with a slot 23 through which a screw 24 passes and by means of which screw and slot the electromagnet is adapted to be adjusted laterally within the casing. 80

An armature 25 is provided for reciprocating the cutter blade 18. This armature has connected with it a spring member 26 and the armature is mounted for vibratory movement 85 by means of a screw 27 which passes through an opening 28 in the armature and is threaded into a post 29 within the casing 15.

The screw 27 co-operates with a clamping member 27^a that rests upon the bottom of 90 the casing to hold the armature and spring against movement about the screw 27 as a pivot.

The armature is supported adjacent one end thereof and the other extremity of the 95 armature is preferably reduced as at 30 and is rounded as at 31 upon its lower face, the reduced portion 30 being arranged at an inclined angle to the armature and projecting over the blade 18 and spaced therefrom. 100

A leaf spring 32 is secured by one end as at 33 to the blade 18. The other end of the spring is shaped to form an open seat 34 having slots 35 in the walls thereof and the bottom of the seat is spaced above the adjacent face of the blade 18 and is rounded to conform to the contour of the rounded lower face 31 of the portion 30 of the armature. The reduced portion 30 of the armature 25 rests within the seat 31, and a pin 36 passes 110

through the end 30 of the armature and enters the slots 35 in the leaf spring 32. The spring and the pin 36 form a resilient connection between the blade 18 and the armature 25. The stress of the armature upon the resilient member 32 serves as a means for holding the plate 18 against the stationary plate 16 and at the same time the armature will have a free movement with respect to the blade 18. The curved surfaces 31 of the portion 30 of the armature and the correspondingly shaped seat in the resilient member 32 will permit the armature and reciprocating blade to relatively rock and thereby insure an equal pressure upon both ends of the reciprocating blade. With this construction the armature may be short and stiff and adapted to spring only in directions towards and away from the magnet, and the spring 32 will provide all the necessary spring or tension on the blade 18.

The stress of the spring 32 may be varied by raising and lowering the end 30 of the armature. This is accomplished by swinging the armature about the pivot formed by the screw 27 after the screw has been loosened.

Any suitable means may be provided for thus adjusting the armature but a simple and efficient means embodies a threaded socket 37 projecting from the other end of the armature. This socket is disposed between spaced lugs or posts 38 in the casing 15 and a screw 39 is threaded into the socket. The screw is provided with an open circumferential groove 40 in the body portion thereof, and stationary pins or lugs 41 carried by the posts 38 extend into the groove 40 of the screw 39 so that the screw will be held against longitudinal movement but when the screw is rotated in any suitable manner, the socket 37 will be moved longitudinally of the screw, with the result that the armature 25 will be rocked or moved about its pivot.

When the socket end of the armature is elevated the extremity 30 will be depressed and this will increase the tension upon the spring 32, likewise when the socket end of the armature is depressed the extremity 30 of the armature will be raised and the tension of the spring 32 will be decreased.

The electromagnet 21 receives its supply of electric current through suitable conductors 42, and these conductors are arranged within the casing 15 and are threaded through an opening 43 in the post 38, a controlling switch 44 being provided within the casing for controlling the current to the magnet.

It will be thus noted that with this improved construction when the electromagnet is energized the armature 25 will be attracted and the extent of this movement of the armature will be controlled by the engagement of a portion 45 of the armature with a portion 46 of the pole piece 22, the armature being at-

tracted against the stress of the spring 26. 65 When the electromagnet is deenergized the armature will return to its normal position.

This vibration of the armature 25 will impart a reciprocating movement to the blade 18. 70

A cover 47 is provided for the casing and this cover is provided with a projection 48 at the forward end thereof and one or more projections 49 on the edge of its body portion, and which projections serve as a means 75 for properly positioning the cover upon the casing, the projections 49 being adapted to enter a suitable recess 50 in the wall of the casing.

A separate vibrator or implement 51 is 80 provided for use in connection with this device, whereby the device may be employed for operations other than clipping operations, and this attachment is adapted to be applied without disconnecting any of the parts of 85 the cutter or clipper mechanism.

To that end the attachment 51 is provided with a stem 52 having a threaded extremity 53 adapted to be threaded into a socket 54 carried by the armature 25, and which socket 90 opens laterally of the armature, the casing 15 being provided with an opening 55 in alignment with the socket 54.

The attachment 51 is adapted to be connected by passing the stem 52 through the opening 55 and threading the extremity of the stem into the socket 54. 95

In use, a long stroke should be given to the armature when using the vibrator attachment, whereas when the implement is used 100 as a clipper it is desirable to impart a shorter stroke to the armature. The vibration of the armature is adapted to be controlled by means of a screw device 56 which is threaded through the cover 47 and is preferably provided with a fibre element 57 secured to the end thereof. The extremity of the screw 56 is adapted to engage a surface 58 carried by the armature 25 and formed in any suitable manner, the surface 58 being provided adjacent the free end of the armature. 110

When the vibrator is employed the extent of operation of the cutter blade will serve as an indicator to indicate the force of operation of the vibrator. 115

When the device is used as a hair clipper, the vibration of the armature may be reduced so that the blade 18 will travel the proper distance and this is accomplished by applying a light downward pressure upon the free end of the armature by forcing the end of the screw 56 against the surface 58, this will result in an increased frictional pressure between the end of the screw 56 and the surface 58 on the armature. 120

When it is desired to produce a longer stroke to the armature this pressure of the screw 56 upon the surface 58 is relieved. 125

It will therefore be manifest that both implements, although they have different functions and operations, are controlled in their operation by the adjustment of the screw

5 56 to regulate or control the extent of vibratory movement of the armature.

As a means for holding the screw in its adjusted position a spring washer 59 is provided which is secured adjacent the lower face 10 of the cover member 47 and is held against rotation by means of an anchoring pin 60.

The washer 59 being of a spring construction, will grip the threaded shank of the screw 56 and will frictionally bind or retain 15 the screw in its adjusted position and thereby prevent the same from working loose under the vibration of the armature.

The fibre element 57 engaging the surface 58 operates to reduce friction.

20 As a means for providing an extended portion into which the screw 61, which secures one end of the pole piece 22, passes (see Figure 8), the bottom of the casing 15 is provided with an upstanding threaded lug 62 which 25 enters a recess 63 in the pole piece 22.

With this improved construction it will be manifest that the device is adapted to be converted from a clipper into a vibrator or massage device without interfering with or dis-

30 mantling any of the parts of the clipper.

This is accomplished by simply attaching the element 51 to the armature.

When desired to use as a clipper, the element 51 may be readily removed.

35 While the preferred form of the invention has been herein shown and described, it is to be understood that various changes may be made in the details of construction and in the combination and arrangement of the several 40 parts, within the scope of the claims, without departing from the spirit of this invention.

What is claimed as new is:—

1. A device of the character described embodying a support, a reciprocable blade 45 mounted on the support, means for reciprocating the blade comprising an electromagnet and an armature adapted to be actuated thereby, a resilient member connected with said blade, and a pin and slot connection between 50 the armature and said resilient member.

2. A device of the character described embodying a support, a reciprocable blade mounted on the support, means for reciprocating the blade comprising an electromagnet 55 and an armature adapted to be actuated thereby, a portion of the armature projecting over and spaced from said blade, and a resilient element disposed between the said blade and the said portion of the armature and forming 60 a connection therebetween, said resilient element having an open seat to receive the said portion of the armature, the contacting portions of the armature and resilient element being correspondingly rounded.

65 3. A device of the character described em-

bodying a support, a reciprocable blade mounted on the support, means for reciprocating the blade comprising an electromagnet and an armature adapted to be vibrated thereby, a portion of the armature extending across 70 and spaced from said blade, a resilient element disposed between the blade and armature, a portion of said element being spaced from the blade, an open seat in said portion of the element adapted to receive the armature, and a loose connection between the said armature and the said portion of the resilient element.

4. A device of the character described embodying a support, a reciprocable blade 80 mounted on the support, means for reciprocating the blade comprising an electromagnet and an armature adapted to be vibrated thereby, a portion of the armature extending across 85 and spaced from said blade, a resilient element disposed between the blade and armature, a portion of said element being spaced from the blade, an open seat in said portion of the element adapted to receive the armature, a loose connection between the said armature and the said portion of the resilient element, and means for adjusting the armature and magnet one with relation to the other.

5. A device of the character described embodying a support, a reciprocable blade mounted on the support, means for reciprocating the blade comprising an electromagnet and an armature adapted to be vibrated thereby, means mounting the armature for 100 pivotal adjustment in directions transverse to the direction of vibration thereof, means for swinging the armature about its pivot, and means forming a connection between the armature and the said blade, the third recited 105 means embodying a screw device having an open circumferential groove and a stationary projection extending into the said groove.

6. A device of the character described comprising a support, a reciprocable blade mounted upon the support, means for reciprocating the blade comprising an electromagnet and an armature adapted to be vibrated thereby, means mounting the armature for pivotal movement on an axis transverse to its direction of vibration, means for positively moving the armature about said pivot in either direction and for maintaining the armature in its adjusted position, and means pivotally connecting the armature with said blade, the 115 axis of the last recited pivot extending in the direction of reciprocation of the blade.

7. A device of the character described comprising a support, a reciprocable blade mounted on the support, means for reciprocating the blade comprising an electromagnet and an armature adapted to be vibrated thereby, a portion of the armature extending across 120 and spaced from said blade, a leaf spring disposed between the blade and armature, means 125

130

securing the spring to the blade, a portion of the spring being spaced from the blade and shaped to form an open seat to receive the armature, the walls of the seat having slots therein, and a pin projecting laterally from the armature and entering the said slots, the stress of the spring operating to hold the blade against the support.

8. A device of the character described comprising a support, a reciprocable blade mounted on the support, means for reciprocating the blade comprising an electromagnet and an armature adapted to be vibrated thereby, a portion of the armature extending across and spaced from said blade, a leaf spring disposed between the blade and armature, means securing the spring to the blade, a portion of the spring being spaced from the blade and shaped to form an open seat to receive the armature, the walls of the seat having slots therein, a pin projecting laterally from the armature and entering the said slots, the stress of the spring operating to hold the blade against the support, and means for adjusting the armature in directions transverse to the direction of its vibration.

9. A clipper including a stationary cutter, a reciprocable cutter co-operating therewith, means for reciprocating the cutter comprising an electro-magnet and an armature adapted to be reciprocated thereby, a separate vibrator attachment, and means for securing said vibrator attachment to the said armature whereby said cutter and said vibrator will be simultaneously rendered active and may be selectively employed, the last recited means embodying means whereby the said vibrator may be readily detached and removed independently of and separately from the remaining parts of the mechanism.

10. A clipper including a stationary cutter, a reciprocable cutter co-operating therewith, means for reciprocating the cutter comprising an electro-magnet and an armature adapted to be reciprocated thereby, a separate vibrator attachment, and means for securing said vibrator attachment to the said armature whereby said cutter and said vibrator will be simultaneously rendered active and may be selectively employed, the last recited means embodying means whereby the said vibrator may be readily detached and removed independently of and separately from the remaining parts of the mechanism, the extent of reciprocation of said cutter with respect to the stationary cutter operating to indicate the force of operation of the vibrator.

11. A device of the character described including a support, a reciprocable blade mounted on the support, means for reciprocating the blade comprising an electromagnet and an armature adapted to be reciprocated thereby, a separate vibrator attachment, means for detachably securing the said attachment to the said armature, and means for

creating friction upon the armature adjacent said attachment for varying at will the length of the vibrating stroke of the armature.

12. A device of the character described including a support, a reciprocable blade mounted on the support, means for reciprocating the blade comprising an electromagnet and an armature adapted to be reciprocated thereby, a separate vibrator attachment, means for detachably securing the said attachment to the said armature, and means for exerting a frictional pressure upon the armature only and at will and in a direction transverse to the direction of vibratory movement of the armature to vary the extent of such vibratory stroke, the said blade and the support upon which it reciprocates being free from said frictional pressure.

13. A device of the character described including a support, a reciprocable blade mounted on the support, means for reciprocating the blade comprising an electromagnet and an armature adapted to be reciprocated thereby, a separate vibrator attachment, means for detachably securing the said attachment to the said armature, a screw device for exerting a frictional pressure upon the armature at will and in a direction transverse to the direction of vibratory movement of the armature to vary the extent of such vibratory stroke, and means for yieldably securing said screw device in its adjusted position.

14. A device of the character described including a support, a reciprocable blade mounted on the support, means for reciprocating the blade comprising an electromagnet and an armature adapted to be vibrated thereby, a socket opening laterally from the armature, a separate vibrator, means connected with the last said vibrator and adapted to be removably secured in the said socket, and means for exerting a frictional pressure upon the armature adjacent the vibrator to vary the movement of the armature.

15. In a clipper a casing having a cover member, a blade fixed relative to the casing, a blade reciprocable transversely of the first said blade, an armature connected with the second recited blade for reciprocating it, an electromagnet for actuating the armature, and means for controlling at will the operation of the armature by the magnet, the said means embodying mechanism for exerting pressure upon the armature in a direction transverse to the direction of vibration of the armature.

16. In a clipper a casing having a cover member, a blade fixed relative to the casing, a blade reciprocable transversely of the first said blade, an armature connected with the second recited blade for reciprocating it, an electromagnet for actuating the armature, means for controlling at will the operation of the armature by the magnet, the said means embodying a screw device for exerting pres-

sure upon the armature in a direction transverse to the direction of vibration of the armature, and means for locking the screw in its adjusted position.

5 17. A device of the character described including a support, a reciprocable blade mounted on the support, means for reciprocating the blade comprising an electromagnet and an armature adapted to be reciprocated thereby, means mounting the armature for pivotal adjustment about an axis transverse to the direction of vibration thereof, a threaded socket connected with the armature, a screw device engaging in said socket, 10 said screw device having an open circumferential groove in the body thereof, and a stationary projection extending into said groove, whereby when the screw device is rotated the said socket will be moved longitudinally of the screw device to move the armature about its said pivot.

18. A device of the character described including a support, a reciprocable blade mounted on the support, means for reciprocating the blade comprising an electromagnet and an armature adapted to be reciprocated thereby, means mounting the armature for pivotal adjustment about an axis transverse to the direction of vibration thereof, a threaded socket connected with the armature, a screw device engaging in said socket, said screw device having an open circumferential groove in the body thereof, a stationary projection extending into said groove, whereby 25 when the screw device is rotated the said socket will be moved longitudinally of the screw device to move the armature about its said pivot, and a resilient connection between the armature and the said blade, the stress of 30 the said resilient connection being varied by the said adjustment of the armature.

19. A clipper including a stationary cutter, a reciprocable cutter co-operating therewith, means for reciprocating the cutter comprising an electro-magnet and an armature adapted to be reciprocated thereby, a separate vibrator attachment, means for securing said vibrator attachment to the said armature whereby said cutter and said vibrator will be simultaneously rendered active and may be selectively employed, the last recited means embodying means whereby the said vibrator may be readily detached and removed independently of and separately from the remaining parts of the mechanism, and means for varying at will the extent of movement of the armature while the degree of pressure of the armature upon the said reciprocating cutter remains constant.

20. A clipper including a stationary cutter, a reciprocable cutter co-operating therewith, means for reciprocating the cutter comprising an electro-magnet and an armature adapted to be reciprocated thereby, a separate vibrator attachment, means for securing said vibrator

attachment to the said armature whereby said cutter and said vibrator will be simultaneously rendered active and may be selectively employed, the last recited means embodying means whereby the said vibrator may be readily detached and removed independently of and separately from the remaining parts of the mechanism, and means for exerting a frictional pressure upon the armature for varying the extent of movement thereof while the degree of pressure of the armature on the reciprocating cutter remains constant.

21. A clipper including a stationary cutter, a reciprocable cutter co-operating therewith, means for reciprocating the cutter comprising an electro-magnet and an armature adapted to be reciprocated thereby, a separate vibrator attachment, means for securing said vibrator attachment to the said armature whereby said cutter and said vibrator will be simultaneously rendered active and may be selectively employed, the last recited means embodying means whereby the said vibrator may be readily detached and removed independently of and separately from the remaining parts of the mechanism, the said vibrator attachment projecting laterally from the armature and disposed intermediate the ends of the armature, and means for exerting frictional pressure upon the armature to vary at will the extent of vibration thereof while the degree of pressure of the armature on the reciprocating cutter remains constant.

22. A device of the character described including a support, a reciprocable blade mounted on the support, means for reciprocating the blade comprising an electro-magnet and an armature adapted to be reciprocated thereby, a massage device connected with the armature, and means for applying friction to the armature and independently of the blade, the visual travel of the reciprocating blade serving to indicate the force or strength of the operation of the massage device.

23. A device of the character described embodying a support, a reciprocable blade mounted upon the support, means for reciprocating the blade including an electro-magnet and an armature adapted to be vibrated thereby, a resilient element carried by said blade and with which element the end of the armature has engagement, the said resilient element extending in a direction lengthwise of the blade, one end of the resilient element being free from and spaced from the blade, and an open seat in the said free end of the resilient element and into which seat the end of the armature rests.

24. A device of the character described embodying a support, a reciprocable blade mounted upon the support, means for reciprocating the blade including an electro-magnet and an armature adapted to be vibrated thereby, a resilient element carried by said blade

and with which element the end of the armature has engagement, the said resilient element extending in a direction lengthwise of the blade, one end of the resilient element being free from and spaced from the blade, and an open seat in the said free end of the resilient element and into which seat the end of the armature rests, the bottom of the seat and the adjacent edge of the armature being correspondingly rounded whereby one will rest within the other.

25. A device of the character described including a support, a reciprocable blade mounted upon the support, means for reciprocating the blade comprising an electromagnet and an armature adapted to be actuated thereby, and a member carried by the said reciprocable blade and with which member the end of the armature has direct engagement to form a connection between the armature and blade, the said connection being shaped to provide a slight relative free rocking movement of the armature and blade one with relation to the

other in a direction transverse to the longitudinal axis of the armature.

26. A device of the character described embodying a support, a reciprocable blade mounted upon the support, means for reciprocating the blade comprising an electromagnet and an armature adapted to be actuated thereby, and a resilient member carried by the said reciprocable blade and with which resilient member the end of the armature has direct and detachable engagement to form a connection between the armature and blade, the contacting portions of the said resilient member and the end of the armature being shaped to provide a slight relative free rocking movement of the armature and blade one with relation to the other and in a direction transverse to the longitudinal axis of the armature.

30. In testimony whereof I have signed my name to this specification, on this 27th day of May, A. D. 1926.

35. WILLIAM J. VAN OSDEL.
